(57) **CLAIM**

The ornamental design for a "bottle," as shown and described.

DESCRIPTION

FIG. 1 is a perspective view of a bottle in accordance with my new design;

FIG. 2 is a front elevation view thereof; the rear elevation view being identical thereto;

FIG. 3 is a right side elevation view thereof, the left side elevation being a mirror image thereof;

FIG. 4 is top plan view thereof; and,

FIG. 5 is bottom plan view thereof.

Subject matter shown in phantom forms no part of the claimed invention.
